UNITED STATES PATENT OFFICE.

PAUL BECKER, OF CLEVELAND, OHIO, ASSIGNOR TO MAX M. KOCH, OF CLEVELAND, OHIO.

COMBINED COAL AND GAS RANGE.

1,078,896.

Specification of Letters Patent. Patented Nov. 18, 1913.

Application filed January 22, 1913. Serial No. 743,529.

To all whom it may concern:

Be it known that I, PAUL BECKER, a citizen of the United States, residing at Cleveland, in the county of Cuyahoga and State 5 of Ohio, have invented new and useful Improvements in Combined Coal and Gas Ranges, of which the following is a specification.

My present invention pertains to cooking 10 ranges of the combined coal and gas type and more particularly to such ranges as have a depressed chamber in communication with the oven at the front of the oven bottom, a gas burner in said chamber, a movable plate for closing said chamber to the oven when coal is to be used as fuel, and a deflector spaced above the oven bottom and 15 designed to cause the products of combustion from the gas burner to pass to the rear 20 of the oven before passing upwardly into the oven.

The object of my invention is to improve the kind of ranges set forth, by the provision of a connection intermediate the deflector and the closure-plate of the burner-chamber, whereby movement of the deflector will be attended by movement of the closure plate.

In the present and preferred embodiment 30 of my invention, the closure-plate and the deflector are so relatively arranged and connected that when the deflector is moved rearwardly the closure-plate will be moved upward and forward to establish communication between the burner-chamber and the space between the oven bottom and the deflector and at the same time close the forward end of said space so as to protect the operator from a flare of the 35 ignited gas, while when the deflector is drawn forwardly, the closure-plate will be moved rearwardly and downwardly to close the burner chamber and isolate the same from the space below the deflector, 40 all as hereinafter described and claimed; and 45 illustrated in the annexed drawings, in which:

Figure 1 is a plan of so much of a range construction as is necessary to illustrate the best practical embodiment of my invention 50 that I have as yet devised. Fig. 2 is a vertical section showing the closure-plate in position to establish communication between the burner-chamber and the space in 55 the oven below the deflector. Fig. 3 is a

view similar to Fig. 2, but with the closure-plate and the deflector in different positions, namely to isolate the burner-chamber from the space below the deflector and to leave the said space open at its forward end. 60 Fig. 4 is a front elevation of the structure with the movable parts in the same positions as in Fig. 3.

Similar numerals of reference designate corresponding parts in all of the views of 65 the drawings.

In furtherance of my invention, a chamber 1 is arranged below the bottom 2 of the oven, at the forward end thereof, and in said chamber is positioned a gas burner 70 3 that extends lengthwise of the chamber and is designed to be supplied with gas from a suitable source of supply.

For closing the chamber 1 when coal is to be used as fuel, a plate 4 is provided. 75 In its horizontal, closed position this plate 4 effectually isolates the chamber 1 and the burner 3 from the oven and protects the burner against injury. The said closure plate 4 is carried by arms 5 which are 80 connected with the oven in such manner that they are adapted to swing and move vertically within certain limits. The arms 5 are formed integral with or are otherwise fixed to the plate 4 so as to assure the arms 85 and the plate moving as a unit, and, by preference, each of the arms is provided with a segmental rack 6.

Movable forwardly and rearwardly in and supported by guideways 7 on the side 90 walls of the oven, is a deflector 8, and said deflector is provided by preference with two racks 9, one for coöperation with each segmental rack 6. From this it follows that when the deflector is drawn forwardly, the plate 4 will be moved from its vertical position downwardly and rearwardly into its horizontal position in which it closes the passage from the burner-chamber to the oven; while when the deflector is moved rearwardly, the plate 4 will be moved from its horizontal position upwardly and forwardly into its vertical position in which it closes the forward end of the space between the oven bottom and the deflector. In the latter position the plate 4 serves to effectually protect the operator when the burner is ignited and also serves to prevent to a certain extent the escape of the heat and other products of combustion from the forward end 100 105 110

of the space between the oven bottom and the deflector.

The rear portion of the deflector 8 is preferably, though not necessarily, provided with suitable apertures as 10 to facilitate the passage of products of combustion given off by the gas burner from the space below the deflector to the space above the same.

As best shown in Fig. 3 the guideways 7 10 are gradually increased in height toward the forward end of the oven. By virtue of this construction it will be manifest that the guideways permit of slight vertical movements of the deflector incidental to the forward and rearward movements thereof as is necessary to the free operation of the closure-plate by the deflector, and this without permitting the upward passage of products of combustion past the side edges of the deflector.

While I prefer to employ a segmental rack on each arm of the closure-plate and two complementary racks on the deflector, I desire it distinctly understood that without involving departure from the scope of my 25 claimed invention, a single segmental rack on one arm 5 and a single rack on the deflector may be employed.

While I have restricted the construction 30 illustrated to the elements comprised in my invention it is to be understood that when the invention is embodied in a combined coal and gas range, the range may be and preferably is provided with such of the usual appendages as are not incompatible with the purpose of the invention. When desired a detachable implement 11, fitted in an aperture of the deflector may be employed as shown in Fig. 1 to facilitate movement of 40 the deflector.

It will further be gathered from the foregoing that in the position shown in Fig. 2, the closure plate 4 will preclude the possibility of the person or clothing of the operator contacting with the flame from the burner 3 when the operator is placing cooking utensils in or removing the same from the oven space above the deflector 8.

While I prefer to employ means for assuring 50 movement of either the closure plate or the deflector on movement of the other, I do not desire to be understood as confining myself to said provision.

Having described my invention, what I 55 claim and desire to secure by Letters-Patent, is:

1. In a combined coal and gas range, an oven, a chamber extending downwardly from the forward portion of the oven bottom, a gas burner in said chamber, guideways on the side walls of the oven; said guideways being gradually increased in height toward the forward end of the oven, a closure plate for the chamber, mounted in 65 the oven to swing and move vertically and

having a segmental rack, and a deflector spaced above the oven bottom and movable rectilinearly and vertically in the guideways and having a rack intermeshed with the segmental rack of the closure plate.

2. In a combined coal and gas range, an oven, a chamber extending downwardly from the forward portion of the oven bottom, a gas burner in said chamber, guideways on the side walls of the oven; said guideways being gradually increased in height toward the forward end of the oven, a movable closure plate for the chamber, a deflector movable rectilinearly and vertically in the guideways, and a connection between the deflector and the closure plate for moving the latter by the former.

3. In a combined coal and gas range, an oven, a chamber extending downwardly from the forward portion of the oven bottom, a gas burner in said chamber, guideways on the side walls of the oven, a movable closure plate for the chamber, a deflector movable forwardly and rearwardly in the guideways, and a connection between the deflector and the closure plate for moving the latter by the former.

4. In a combined coal and gas range, the combination of an oven, a burner chamber extending downwardly from the bottom thereof, a gas burner in said chamber, a movable deflector spaced above the oven bottom, a movable closure-plate constructed and arranged in one position to close the chamber and in another position to close the space between the oven bottom and the deflector, and a connection intermediate the deflector and the closure plate, whereby movement of one will be attended by movement of the other.

5. In a combined coal and gas range, the combination of an oven, a burner chamber extending downwardly from the bottom thereof, a gas burner in said chamber, a movable deflector spaced above the oven bottom, a movable closure plate constructed and arranged in one position to close the chamber and in another position to close the space between the oven bottom and the deflector, a rack on the deflector, and a segmental rack on the closure plate and intermeshed with the rack on the deflector.

6. The combination in a range, of an oven, a burner chamber extending downwardly from the forward portion of the oven bottom, a movable deflector spaced above the oven bottom; a movable closure plate adapted in one position to close communication between the chamber and space, and in another position to close the forward end of the space, and a connection intermediate the deflector and the closure plate whereby movement of one moves the other.

7. In a range, the combination of an oven, a burner chamber, movable deflecting-means

in the oven, movable means for controlling communication between the chamber and the oven, and a connection intermediate the first-named movable means and the second-named movable means, whereby movement of one brings about movement of the other.

8. In a combined coal and gas range, an oven, a deflector arranged in the oven and spaced above the bottom thereof, means connecting the spaces below and above the deflector at the back of the oven, a burner chamber extending downwardly from the oven bottom adjacent the front thereof, a gas burner in said chamber, and a movable closure plate that in one position closes the burner chamber to the space below the deflector and in another position closes the forward end of said space.

16 In testimony whereof I have hereunto set my hand in presence of two subscribing witnesses.

PAUL BECKER.
